JOSIAH GRIMES, OF WHITTIER, CALIFORNIA, ASSIGNOR OF ONE-HALF TO BIRD F. LYITTLE, OF LOS ANGELES, CALIFORNIA.

DELIVERY DEVICE FOR SUGAR, &c.

1,017,210.

Specification of Letters Patent.

Patented Feb. 13, 1912.

Application filed April 3, 1911. Serial No. 618,712.

To all whom it may concern:

Be it known that I, JOSIAH GRIMES, a citizen of the United States, residing at Whittier, in the county of Los Angeles and 5 State of California, have invented a new and useful Delivery Device for Sugar, &c., of which the following is a specification.

This invention relates to a device for dispensing or delivering divided solid materials, such as sugar, salt, rice, beans, etc., and is particularly adapted for use in groceries as a counter fixture, the invention when applied to this purpose being adapted to withdraw the material from a bin beneath the counter and to elevate the same and deliver it to packages above the counter.

One object of the invention is to provide means for feeding and delivering articles of the character above stated in convenient and rapid manner.

Another object of the invention is to provide a counter fixture for the stated purpose which will not interfere with the use of the counter for other purposes.

25 A further object of the invention is to provide a device of the character stated in which the delivery can be shifted to different positions according to requirements.

Other objects and advantages of the invention will appear hereinafter.

The accompanying drawings illustrate the invention, and referring thereto:

Figure 1 is a vertical section of the device. Fig. 2 is a section on line x^2-x^2 in 35 Fig. 1.

1 designates a counter which may be provided with a hinged closure or door 2 for access to a bin 3 located beneath the counter. Said bin is preferably funnel-shaped and 40 opens at its lower end into a horizontal tube 4 communicating at one end with a vertical tube 5, said vertical tube 5 extending through and above the counter and provided at its upper end with a delivery spout 45 or nozzle 6. A plate 7 may be provided in bin 3, said plate being movable to contract the outlet of the bin to any desired extent.

Means are provided in the tubes 4 and 5 for forcing the material from the bin 3 through said tubes to the delivery spout. The material forcing means in the tube 4 consists of a screw 8 carried by a shaft 9 journaled in bearings 10 and 11 at the ends of the tube 4, said shaft 9 being connected to 55 suitable driving means, as hereinafter set

forth, whereby the screw is rotated to cause the material to be forced in the tube 4 toward the tube 5. Such forcing of the material involves back pressure on the shaft 9 and this is taken preferably by a ball bearing 12, a packing 13 being provided for this bearing compressed by a follower plate 14 within the tube 4 to prevent the sugar or other material within the tube from reaching the ball bearing.

The material forcing means in the tube 5 consists of a screw 15 carried by a vertical shaft 16, the lower end of said shaft being mounted in a bearing 17 at the lower end of the tube 5 and provided with a ball bearing 18 to take the vertical thrust and with packing 19 and follower plate 20 to prevent the sugar or other material from being forced out of the tube 5 and into the ball bearing. The upper end of the shaft 16 is journaled in a bearing 23 in the upper portion of the spout 6, this upper portion of the spout 6 being in the form of a goose-neck or inverted U. A closure cap 24 may be provided over the upper end of the shaft 16.

The spout member 6 extends obliquely downward from the bend at the upper end, or the goose-neck portion thereof, the other leg or end of said goose-neck portion extending vertically downward over the tube 5 and having at its lower end an annular flange 27 resting on an annular flange 28 on top of the tube 5, a stuffing box being provided at the joint of these members, consisting, for example, of a screw collar 30 screwing on the flange 28 and a packing 31 held between said screw collar and the flange 27. This connection of the spout with the tube 5 permits of angular movement of the spout to different positions over the counter. The spout is also preferably extensible to enable its lower end to be adapted to different sizes of packages or bags to be filled. For this purpose a plurality of telescoping sleeves 32, 33 may be provided, sleeve 32 sliding on the spout 6 and the sleeve 33 sliding on the sleeve 32 and each of said sleeves being provided with a projection 37 engaging in a bayonet slot 38 in the member on which it slides. A sliding gate 39 may be provided at the lower end of the lower sleeve 33.

Any suitable driving means may be employed for rotating the screw carrying shafts 9 and 16. As shown in the drawings, the shaft 9 carries a wheel 40 connected by a
